(57) **CLAIM**

The ornamental design for a belt adapted to hold a cane, as shown and described.

DESCRIPTION

FIG. 1 is a perspective view of a belt adapted to hold a cane showing our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side view thereof; and,

FIG. 7 is a left side view thereof.

The features shown in broken lines in FIG. 1 are shown for illustrative purpose only and form no part of the claimed design.
